FRAME FOR MAKING FRINGE

Jeannette L. Webb, P.O. Box 287,
Madison, N.J. 07940

Filed May 8, 1972, Ser. No. 251,576

Term of patent 14 years

Int. Cl. D15—06

U.S. Cl. D3—19 A

FIG. 1

FIG. 2

FIG. 1 is a perspective view of a frame for making fringe showing my new design, the back being plain with portions continuing as indicated, the yarn shown in broken lines being for purposes of illustration only; and

FIG. 2 is a section through the plane indicated by the arrows 2—2 of FIG. 1.

I claim:

The ornamental design for a frame for making fringe, as shown and described.
